ABSTRACT OF THE DISCLOSURE

A piston and cylinder combination for multiplying forces wherein one cylinder is telescopically received in the other. A piston is slidably received in the inner cylinder and the piston is fixed to the outer cylinder. A pipe extends through the inner cylinder into a space between the inner cylinder and the outer cylinder to supply air under pressure to this space. An opening in the pipe admits air into the inner cylinder between the piston and the inner cylinder, and an exhaust pipe is connected to the space between the inner cylinder and the outer cylinder on the remote side of the piston from the space that receives air from the opening in the pipe.

This invention relates to molding machines and, more particularly, to means for compressing sand in a molding machine.

In the green sand foundry industry, there is a common type of molding machine wherein the sand is squeezed in flasks around a pattern. Sometimes this molding machine utilizes a hydraulic cylinder to exert the pressure on the sand. It has been discovered that by providing a cylinder that multiplies the pressure air already available at the molding machines, it is possible to compress the sand by means of air in the cylinder and to dispense with the hydraulic cylinder. This thereby eliminates the need of a hydraulic system on the machine.

It is, accordingly, an object of the present invention to provide an improved molding machine.

Another object of the invention is to provide an improved means to compress sand in a molding machine.

Still another object of the invention is to provide a molding machine which is simple in construction, economical to manufacture, and simple and efficient to use.

With the above and other objects in view, the present invention consists of the combination and arrangement of parts hereinafter more fully described, illustrated in the accompanying drawings and more particularly pointed out in the appended claims, it being understood that changes may be made in the form, size, proportions, and minor details of construction without departing from the spirit or sacrificing any of the advantages of the invention.

In the drawings:

FIG. 1 is a front view of a molding machine according to the invention;

FIG. 2 is a side view of the machine shown in FIG. 1;

FIG. 3 is an enlarged view partly in cross section showing the improved piston and cylinder combination;

FIG. 4 is a schematic view of the piston and cylinder combination showing the piston and cylinder before air is admitted thereto;

FIG. 5 is a view similar to FIG. 4 showing the combination with compressed air inserted into the chambers and the piston and cylinder extended relative to each other; and

FIG. 6 shows the piston and cylinder combination of FIGS. 4 and 5 during the retraction part of the cycle.

Now with more particular reference to the drawings,

2

the molding machine shown in FIGS. 1 and 2 has a frame 10 that has a conveyor 11 suitable to support a flask 12. The frame supports a squeeze board 13. A supply of compressed air is provided thru the valve mechanism 14 which is connected to the pipes E and D in a suitable manner.

The piston and cylinder combination 15 is supported on the machine frame and supports the squeeze unit which is a piston and cylinder combination rigidly and provides a reaction member for supplying a reaction force on the squeeze unit during the time the sand is being compressed.

The first cylinder 17 has a closed top and wall as indicated. The closed top 18 has a piston rod 19 fixed to it which extends down through the closed top 20 of the second cylinder 21 and has a sealing washer 22 disposed in a groove around the outer periphery of the piston 23 which makes sealing engagement with the inside of the cylinder 21. Likewise, a sealing ring 24 is disposed in the internal peripheral groove in the cylinder 17 which makes sealing engagement with the outside surface of the cylinder 21. Thus, the piston 23, along with the inside of the cylinder 21 and the bottom, forms a second chamber C while a first chamber A is formed as shown.

High pressure may be admitted through the pipe D which escapes into the second chamber through the opening 28 and escapes into the first chamber from the end at 29. The air is exhausted through the pipe E from chamber C. Thus, the force of air in the first chamber A is exerted on the closed top 18. The force of the air in chamber C is added to the first mentioned force directly since it is transmitted from piston 23 through piston rod 19 to the closed top 18 which would react on the sand to compress it.

The squeeze unit is shown in more detail in FIG. 3 and it will be noted that air will be admitted to chamber C from pipe D and through the opening 28 into the pipe shown and out the end 29 to the chamber A. Air will be exhausted from the two chambers in a like manner in a reverse direction through pipe 19 and pipe E.

Thus, the effect of air pressure will be in substance doubled by the arrangement of cylinders in the squeeze unit.

The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

1. A piston and cylinder combination for multiplying forces in molding machines comprising a first cylinder and a second cylinder, said first cylinder and said second cylinder each having a side wall and a closed end, said second cylinder being telescopically received in said first cylinder, means forming a seal between the walls of said first cylinder and the walls of said second cylinder whereby a chamber for fluid is formed by the inside of said first cylinder and the outside of said second cylinder, a piston rod attached to said first cylinder and extending through said second cylinder and into said second cylinder, a piston attached to said piston rod, said piston slidably engaging the inside of said second cylinder, closing means closing the end of said second cylinder

whereby a second chamber is formed by said second cylinder, said piston, and said closing means, and means to admit fluid under pressure into said first chamber, and means to admit fluid under pressure into said 5 second chamber,

said means to admit fluid under pressure comprising a single conduit connected into said second chamber and through said piston into said first chamber, said conduit having means to admit fluid thereinto to 10 exhaust fluid from said first chamber and from said second chamber.

2. The piston and cylinder combination recited in claim 1 in combination with a molding machine having a frame, said molding machine having means thereon to support 15

a flask with sand therein, said piston and cylinder combination being supported on said frame,

and means on said piston and cylinder combination adjacent said flask for engaging said sand and adapted 20 to compress said sand when fluid under pressure is admitted into said chambers.

3. The combination recited in claim 1 wherein said conduit means comprises an exhaust pipe extending through said closing means into said second chamber and further extending through said 25 piston and communicating with said first chamber, a pressure pipe communicating with said first chamber and said second chamber,

said exhaust pipe and said pressure pipe extending through said piston, and sealing means between said piston and said pressure pipe and between said piston and said exhaust pipe slidably engaging said pipes whereby said piston may slide relative to said pipes.

4. The piston and cylinder combination recited in claim 3 in combination with a molding machine, said molding machine having a frame, and means on said frame to support a flask with sand therein to be compressed, said piston and cylinder combination being supported on said frame adjacent said sand, said piston and cylinder combination being adapted to engage said sand to compress it.
